UNITED STATES PATENT OFFICE.

FRANK EUGENE THOMPSON, OF LAKE CITY, FLORIDA.

COLLAPSIBLE DRUM.

961,556.

Specification of Letters Patent. Patented June 14, 1910.

Application filed December 15, 1909. Serial No. 533,227.

To all whom it may concern:

Be it known that I, FRANK EUGENE THOMPSON, a citizen of the United States, residing at Lake City, in the county of Columbia and State of Florida, have invented certain new and useful Improvements in Collapsible Drums, of which the following is a specification.

My invention relates to an improvement 10 in collapsible drums, and the object is to provide means whereby the shell can be assembled readily and the heads connected to the shell.

The invention consists in certain novel 15 features of construction and combinations of parts which will be hereinafter described and pointed out in the claims.

In the accompanying drawings:—Figure 1 is a perspective view of the drum; Fig. 2 20 is a view showing two of the sections of the shell connected together; Fig. 3 is a detail sectional view; and Fig. 4 is a view of one of the heads of the drum folded.

A represents the shell of the drum, which 25 is made in sections, preferably four, each section being connected to the other by means of hooks and eyelets, 1 and 2. Plates 3 are formed upon the sections for forming a tight joint, the plate on one section overlapping 30 the plate on the other section, so that the joint is sealed. The drum head is provided with reinforcing strips 4 and 5, which are semicircular in shape and are connected to the drum along the edges thereof. The 35 two strips are hinged together, which allows the head to be folded as indicated in Fig. 4. The strips 4 and 5 are adapted to extend down along the exterior of the shell A. Extending around the edges of the drum are 40 rims 6. These rims are made in sections, and are hinged together by hinges 7, 7. The hinges are connected together by means of cotter pins 8, although they might be connected by bolts, but I have only disclosed 45 the connection by means of cotter pins, as this forms an easy means of disconnecting the sections, when it is desired to fold the drum. These rims rest upon the strips 4 and 5, which are around the edge of each

head. The rims protrude beyond the heads 50 B of the drum, and connecting the two rims together are vertical bolts or rods 9, 9. Hooks 10 are on one end of the rods, and hooks 11 have screw threaded engagement with the other terminals or ends of the rods 55 9. These hooks 10 and 11 are adapted to be placed over the rims 6, and upon turning the rods 9, the rims will be drawn toward each other, which causes the drum to be tightened, to obtain the proper tone. 60

I have disclosed a structure which can be readily assembled, and the parts easily disconnected, whereby the shell can be separated into four sections, allowing it to be packed in a small case. Both heads are 65 capable of being folded, which allows them to be inserted into a case, and the rims, which are provided with hinges, can be folded upon each other and placed in the case. By providing means whereby a drum 70 can be collapsed and placed in a small case, it can be easily transported from place to place without much trouble. It is generally the custom to take a drum, and especially the bass drums, in their normal shape, or 75 shape in which they are operated.

Having fully described my invention, what I desire to secure by Letters Patent, is:—

1. A collapsible drum comprising a segmental sectional shell, said sections removably connected together, heads mounted upon the shell, rims made in sections and connected to the heads, and means for drawing the rims toward each other for tightening the heads upon the shell. 85

2. A collapsible drum comprising a segmental sectional shell, foldable heads mounted upon the shell, rims made in sections, said sections being removably connected together, and means for engaging the rims 90 for drawing them toward each other for tightening the heads upon the shell.

In testimony whereof I affix my signature, in the presence of two witnesses.

FRANK EUGENE THOMPSON.
